(57) CLAIM

The ornamental design for "kiosk", as shown and described.

DESCRIPTION

FIG. 1 is a left side elevational view of a kiosk showing my new design;

FIG. 2 is a front elevational view thereof, the rear elevational view being identical thereto;

FIG. 3 is a right side elevational view thereof;

FIG. 4 is a top plan view thereof;

FIG. 5 is a bottom plan view thereof;

FIG. 6 is a sectional view thereof taken generally along sectional lines 6—6 of FIG. 2; and,

FIG. 7 is a perspective view thereof.
